UNITED STATES PATENT OFFICE.

JOHN M. CURTICE, OF LOWELL, MASSACHUSETTS.

YARN GUIDE AND CLEARER.

SPECIFICATION forming part of Letters Patent No. 448,296, dated March 17, 1891.

Application filed March 19, 1888. Serial No. 267,614. (No model.)

To all whom it may concern:

Be it known that I, JOHN M. CURTICE, a citizen of the United States, residing at Lowell, in the county of Middlesex and Commonwealth of Massachusetts, have invented a certain new and useful Improvement in Yarn Guides and Clearers, of which the following is a specification.

My invention relates to yarn guides and clearers; and it consists in the devices and combinations hereinafter described and claimed, which have for their object the support of the supporting-rail, securing the guides and clearers in a proper position to said rail, and means of adjusting said guides and clearers and of preventing the same from getting out of position.

In the accompanying drawings, Figure 1 is a perspective view of a yarn-supporting rail, 20 one of the supporting-posts, the upper part of the lifting-rod, and the yarn guides and clearers supported on said rail; Fig. 2, a front elevation of a guide and clearer and of a part of the supporting-rail; Fig. 3, a rear elevation 25 of the same; Fig. 4, a vertical section on the line $x-x$ in Fig. 2; Fig. 5, an isometric view of the clamp detached from the guide; Fig. 6, a front elevation of the upper part of a supporting-post and a part of the supporting-rail; Fig. 7, a horizontal section on the 30 line $x-x$ in Fig. 6; Fig. 8, a side elevation of the upper part of said post and a cross-section of the supporting-rail. In the remaining figures a modification of my invention is represented, Fig. 9 being a plan of the same and 35 a part of the supporting-rail; Fig. 10, a front elevation; Fig. 11, a section on the line $y-y$ in Figs. 10 and 13; Fig. 12, a rear elevation of the same, and Fig. 13 a vertical section on 40 the line $z-z$ in Fig. 12.

A is a supporting-post supporting the supporting-rail B. The supporting-post A is secured in the usual manner by means of a collar a on the lower end of said post and 45 a set-screw a', turning radially in said collar to the lifter-rod A', carried by the supporting-rail. (Not shown.) Most commonly the supporting-rail B is cylindrical, and is prevented from turning in the supporting-post 50 by a set-screw which passes into the front of the post near the top of the same and

thrusts against the rail, and sometimes the rail has a flat side to receive the thrust of said screw. I flatten one side of the rail B at b for a different purpose. The posts A near 55 their upper ends are hollowed out at a² to receive the convex part of said rail, and I secure to the post A, near the top of the same, a clamp-piece a³ by means of a screw a⁴, said clamp-piece being flat on the rear side 60 and bearing against the flat side of the supporting-rail. This construction allows any post to be disengaged from the rail without disengaging any other post therefrom, and allows the adjacent ends of two sections of 65 the supporting-rail to be supported by one post. (See dotted lines in Fig. 6.) The clamp-piece a³ is prevented from turning by a vertical groove a⁵ therein engaging a vertical rib a⁶ on the post. (See Fig. 7.) The base 70 c of the yarn guide and clearer is flat on its rear surface, and is held against the flat side b of the rail B by a clamp c', provided with an opening c² to embrace the convex side of said rail B, said clamp being secured 75 to the base c by a clamp-screw c³, which passes through a washer c⁴ and through a vertical slot c⁵ into a tapped hole c⁶ in the lower part of said clamp, said vertical slot allowing the base of the yarn guide and clearer to be 80 raised and lowered on the supporting-rail in an obvious manner.

To prevent the base c from turning on the supporting-rail, the upper end of the clamp c' is provided with a tongue c⁸, which enters 85 and fits a vertical groove c⁹ in the back of the base c, so that when the clamp-screw c³ is turned up the base and clamp cannot turn upon each other.

The upper part of the base c is provided 90 with a horizontal portion, over which the yarn is drawn in the operation of said guide and clearer, and the yarn-knife D is held parallel with the horizontal top of said base by means of a shank or downward projection d on said 95 knife entering a vertical groove c¹⁰ in the base c, the opening between the top of said base and the straight lower edge of the knife being adjustable by means of a slot d', through which the holding-screw d² is driven into said 100 base.

The yarn is prevented from being drawn out

from under the yarn-knife by a yarn-gate E of the construction shown in another application, Serial No. 34,576, filed by me May 31, 1881, and now pending. Said yarn-gate E is pivoted at e within a recess c^{16} , formed in the base c, and shown by dotted lines in Figs. 2 and 3, in such a manner that the weight of said gate causes its pointed end e' to be in contact at all times with the inclined free end of the knife D, except when a yarn is being introduced into the guide. A yarn-rest F of the form shown is secured to the base c in such a manner as to almost conceal the yarn-gate and extends along parallel with the front face of the base c at the upper edge of said yarn-rest, except at the ends of the yarn opening or space between the knife D and the base c, where it is carried upward at f' with a gradual curvature, as shown in Fig. 2 and described and claimed in said previous application. Between the points f' the yarn-rest is rounded downward and forward to present a large surface to the yarn to lessen the wear of the yarn thereon. The yarn-rest is secured to the base c by means of rivets e f^2 passing through an ear f^3 , with which said rest is provided, one e of said rivets serving as the pivot of the yarn-gate, and the said ear f^3 forming a removable cap for the insertion of the yarn-gate. The operative portion of the yarn-rest is made very thin, so as to be chilled in casting and by its hardness to resist wear.

In the modified form of my invention shown in Figs. 9 to 13 the base c^{11} is clamped to the rod, as above described; but the clamp-screw c^3 also serves to hold the yarn-rest in proper position, said yarn-rest F' being provided with a vertical shank f^4 , having a vertical slot f^5 , through which and through a vertical slot c^5 in the base c^{11} , as above described, said clamp-screw passes into the clamp c' , so that the base and the yarn-rest are adjustable in height with reference to the clamp, but not with reference to each other, the lower end of the shank resting upon a ledge or projection c^{12} , cast on the base, as shown in Fig. 13, and being prevented from turning partly by said ledge and partly by a vertical rib c^{13} on the base and a vertical groove f^6 in said yarn-rest. The base c^{11} extends above the yarn-knife D' along the entire upper edge of said knife and prevents the knife being accidentally struck and knocked downward in such a manner as to close or diminish the space between said knife and the yarn-clearing surface of the base.

The yarn-knife D' is adjustable vertically by means of a slot d^4 in said yarn-knife, through which the holding-screw d^5 is driven into the base, and is guided by its vertical side or edge d^6 , resting against a vertical shoulder c^{14} on the base c^{11} to keep the lower edge of said yarn-knife parallel with the yarn-clearing surface of said base.

The yarn-gate E' is a finger pivoted at its upper end on a horizontal yarn-gate stud c^{15} ,

projecting from the base c^{11} against the back of the yarn-knife, so that the yarn-knife may be adjusted vertically without moving said gate. The yarn-gate E' is longer than the distance from its pivot to the yarn-clearing surface of the base, upon which surface the lower end of said finger rests, said finger standing in an inclined position with its lower end a little nearer the middle of the guide than its pivoted end, and its lower end on the inner side may be provided with notches e^2 to catch the yarn when an attempt is made by doubling the yarn around the lower end of the finger to remove it from the guide.

I do not herein claim either the support-piece (or base) having a chamber to receive the automatic stop-gate, in combination with the cap of said chamber, having a yarn rest or supporter extended from said cap, or the combination of such support-piece and yarn-supporter having inclines at its ends with an adjustable portion or yarn-knife, as these combinations are described and claimed in said application, Serial No. 34,576, above referred to.

I claim as my invention—

1. The combination of the base having a flat surface, the supporting-rod having a correspondingly-flat surface, a clamp hollowed to receive said rod, and a clamp-screw to draw said base and clamp against said rod and to hold the flat surface of said base against the flat side of said rod and to prevent said base and clamp from turning on said rod, as and for the purpose specified.

2. The combination of the supporting-rod having a flat side, the base having a corresponding flat surface and having a vertical slot, a clamp hollowed to receive said rod, and a clamp-screw arranged in said vertical slot and entering said clamp to draw said base and clamp against said rod and to hold the flat surface of said base against the flat side of said rod to prevent said base and clamp from turning on said rod and to allow said base to be adjusted vertically on said rod, as and for the purpose specified.

3. The combination of the supporting-rod having a flat side, the base having a corresponding flat surface, a clamp hollowed to receive said rod and provided with a tongue to enter an opening with which said base is provided, and a clamp-screw to draw said base and clamp against said rod and to hold the flat surface of said base against the flat surface of said rod to prevent said base and clamp from turning on said rod or on each other, as and for the purpose specified.

4. The combination of the supporting-rod having a flat side, the base having a corresponding flat surface and having a vertical slot, a clamp hollowed to receive said rod and provided with a tongue to enter a vertical groove with which said base is provided, and a clamp-screw arranged in the vertical slot of said base and connecting said base to said clamp to draw said base and clamp against said rod to prevent said base and clamp from

turning on each other and to allow said base to be adjusted vertically on said rod, as and for the purpose specified.

5. The combination of the base provided with a clearing-surface and with a ledge, and the yarn-rest adapted to rest upon said ledge with its yarn-supporting surface in the same horizontal plane with said clearing-surface, and means, substantially as described, for securing said base and yarn-rest to each other, as and for the purpose specified.

6. The combination of the supporting-rod, the base provided with a clearing-surface and with a ledge, and the yarn-rest adapted to rest upon said ledge with its yarn-supporting surface in the same horizontal plane with said clearing-surface, and means, substantially as described, for adjustably securing said base and yarn-rest upon said supporting-rod, as and for the purpose specified.

7. The combination of the supporting-rod, the base provided with a clearing-surface and having a vertical slot and a ledge, the yarn-rest adapted to rest upon said ledge with the top of its yarn-surface in the same horizontal plane with said clearing-surface and provided with a vertical slot, a clamp, and a clamp-screw passing through both of said slots and into a threaded hole in said clamp to secure said base and yarn-rest to said supporting-rod and to keep said yarn-surface and said clearing-surface in their proper relative position while said base is being adjusted on said rod, as and for the purpose specified.

35 8. The combination of the base provided with a yarn-clearing surface and with a recess,

a horizontal stud secured to said base within said recess, a yarn-gate pivoted on said stud, and a yarn-knife secured to said base to cover said yarn-gate and stud and to retain said gate upon said stud, and means, substantially as described, for adjusting said yarn-knife vertically to enable said knife to be adjusted without changing the position of said yarn-gate, as and for the purpose specified.

9. The combination of the supporting-rod having a flat side, the supporting-post hollowed out to receive said rod, a clamp-piece having a flat side to rest against the flat side of said rod, a screw to secure said clamp-piece to said post, and one or more yarn-guides secured to said rod, as and for the purpose specified.

10. The combination of the supporting-rod having a flat side, the supporting-post hollowed out to receive said rod, a clamp-piece having a flat side to rest against the flat side of said rod, a screw to secure said clamp-piece to said post, said post having a vertical rib and said clamp-piece having a vertical groove to receive said rib and to prevent said clamp from turning on said post, and one or more yarn-guides secured to said rod, as and for the purpose specified.

In witness whereof I have signed this specification, in the presence of two attesting witnesses, this 30th day of January, A. D. 1888.

JOHN M. CURTICE.
